SPANNER WRENCH FOR WATERPROOF WATCHES

Robert A. Williams, Denver, Colo.

Application January 15, 1945, Serial No. 572,828

3 Claims. (Cl. 81—6)

1

This invention relates to a spanner wrench, and is more particularly designed for removing the backs from waterproof watches. Such watches have their backs threaded into the cases, and the backs are formed with a variety of types of wrench-receiving devices. Each watch manufacturer furnishes a special wrench to fit his particular type of watch back, thus requiring the usual watchmaker to carry an infinite variety of wrenches in order to service all types of watches.

The principal object of this invention is to provide a single universal wrench, by means of which all of the present-known varieties of waterproof watch backs may be removed and replaced.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a top-view of the improved wrench;

Fig. 2 is a longitudinal section therethrough taken on the line 2—2, Fig. 1;

Fig. 3 is a bottom view of the wrench as it would appear when set to accommodate a given type of watch back; and

Figs. 4, 5, 6, and 7 illustrate four of the many types of watch case backs which the improved wrench will accommodate.

The improved wrench consists of a relatively flat elongated handle member 10 having a hanging opening 11 in one extremity and a stationary fulcrum pin 12 formed on or secured in the other extremity so as to project at right angles to the plane of the handle. A longitudinally extending slot 13 is formed along the center line of the handle member 10 adjacent the fulcrum pin 12.

A pin disc 14 is detachably secured against the lower face of the handle member 10 by means of a threaded stud 15, which extends upwardly through the slot 13, terminating in a thumb nut 16.

A slide plate 17 is positioned between the handle member 10 and the nut 16. The plate 17 is provided with a suitable opening for the passage of the stud 15 and is formed with ears 18 which are bent around the handle member 10 to maintain the plate 17 in alignment therewith as it is slid longitudinally therealong. One extremity

2

of the slide plate 17 is turned upwardly to form a thumb-engaging tab 19.

Four back-engaging pins 20, 21, 22, and 23 are fixed in, and extend downwardly from the pin plate 14. A locking pin 24 is affixed in the slide plate 17 forwardly of the stud 15 and extends downwardly through the slot 13 sufficiently far to engage in locking holes 25, 26, and 27 in the plate 14. Each of the pins 12, 20, 21, and 23 terminates in a relatively small entering point 28. The pins 20 and 21 are positioned 90° apart around the axis of the stud 15 and the pins 22 and 23 are positioned 120° apart around the same axis.

15 To assist in describing the use of the wrench, several typical watch backs are illustrated. A typical watch back 29 is illustrated in Fig. 4, having notches 30 formed in its peripheral edge at 120° intervals. Other backs have intermediate notches, as indicated in broken line at 31 at 60° intervals. Still other watch backs of this type have two or four notches set at intervals of 180° or 90°, respectively.

Another form of watch back is illustrated at 25 33 in Fig. 5 having a plurality of flat wrench faces 34. The backs 33 in some instances have twelve faces 34 as illustrated, and in other instances have six, eight, or sixteen faces.

A different type of watch back is illustrated at 30 35 in Fig. 6 having two spanner wrench depressions 36 placed opposite each other in the back. Other backs of this type have four spanner wrench depressions positioned such as indicated in broken line at 37.

35 A fourth form of watch back is illustrated at 38 in Fig. 7, having arcuate indentations 39 in its periphery. On some watches the indentations 39 are at 30° intervals, and on others at 45° intervals.

40 The improved wrench is designed for use on all of the above types of watch backs, in addition to others not shown.

For use on the back 32 with the notches 30 at 30° or 60° intervals, the pin plate 14 is rotated 45 to place the locking hole 40 over the locking pin 24. This places the pins 22 and 23 opposite the pin 12, the three being spaced at 60° intervals. The point 28 of the pin 12 is engaged in a notch 30 on the far side of the back and the slide plate 50 17 is pressed forwardly with the thumb against the tab 19 to force the two pins 22 and 23 into the remaining notches 30 until they snugly engage the back 32. The thumb nut 16 is then tightened and the wrench is firmly attached to the watch back and can be readily used for re-

moving and replacing the latter, with the handle 10 acting as a lever. Should the back have the additional notches 31, the latter are not used, since the pins need only to engage the alternate notches 30.

Should the watch back 32 have its notches 30 spaced at 45° or 90° intervals, the pin plate 14 is rotated to place the locking hole 26 over the locking pin 24, as shown in Fig. 3. This places the 90° pins 20 and 21 in position to cooperate with the fixed pin 12. The pins are then adjusted to the notches by manipulation of the slide plate, as previously described. Should the back 32 have only two, oppositely-placed notches, the pin plate 14 is rotated to place the locking hole 25 over the pin 24. This places the pin 23 directly opposite the pin 28 so that they will engage notches on opposite sides of the back when forced thereagainst by pressure on the thumb tab 19.

For use on the back 33 the same procedure is followed, that is, the pins 20 and 21 are used on backs having eight or sixteen faces 34, and the pins 22 and 23 being used on backs having six or twelve of the faces 34. The pins are forced snugly against the faces by pressure on the thumb tab and are locked in the engaged position, as indicated in broken line in Fig. 5, by means of the thumb nut 16.

For use on the watch back 35, the plate 14 is rotated to bring the hole 25 over the stud 24 to bring the pins 12 and 23 into alignment so that they may be inserted in the two depressions 36. The proper spacing is obtained by shifting the slide plate 17 before the thumb nut 16 is tightened. This same procedure applies regardless of the number of depressions 36 and 37 in the watch back 35.

For use on the back 38 the plate 14 is rotated to bring either the two pins 20 and 21 or the two pins 22 and 23 into place in the indentations 39, as shown in broken line in Fig. 7. The choice of pins, of course, depends upon the spacing of the indentations. The operation on this type is very similar to that on the back 32 of Fig. 4.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A wrench for rotating watch case backs comprising: an elongated handle member; a first pin projecting from one extremity of said handle member at right angles to the axis of the latter; a pin plate; a pivot stud extending from said pin plate through an elongated slot in said handle

member; a clamping nut on said stud acting to clamp said plate to said handle member; and a second pin projecting from said pin plate with its axis parallel to the first pin and eccentric of said stud.

2. A wrench for rotating watch case backs comprising: an elongated handle having a longitudinally extending slotted opening; a pin projecting from said handle adjacent one extremity thereof and at right angles to the plane thereof; a pin plate positioned against one face of said handle member; a pivot stud projecting from said pin plate through said elongated opening; a slide plate engaging the other face of said handle member, said stud passing through said slide plate; a nut on said stud acting to clamp said slide plate and said pin plate to opposite sides of said handle member; wrench pins projecting from said pin plate parallel to said first pin, said wrench pins being placed to one side of the axis of said stud; and means extending from said slide plate to said pin plate through said elongated opening for locking said pin plate at pre-set circumferential positions.

3. A wrench for rotating watch case backs comprising: an elongated handle having a longitudinally extending slotted opening; a pin projecting from said handle adjacent one extremity thereof and at right angles to the plane thereof; a pin plate positioned against one face of said handle member; a pivot stud projecting from said pin plate through said elongated opening; a slide plate engaging the other face of said handle member, said stud passing through said slide plate; a nut on said stud acting to clamp said slide plate and said pin plate to opposite sides of said handle member; wrench pins projecting from said pin plate parallel to said first pin, said wrench pins being placed to one side of the axis of said stud; and a locking pin extending from said slide plate through said elongated opening, there being openings in said pin plate for receiving said locking pin to locate and lock the former at predetermined circumferential positions.
